[57] **CLAIM**

The ornamental design for bracket for attachment of a vacuum gauge or the like, substantially as shown and described.

DESCRIPTION

FIG. 1 is a rear elevational view of the bracket for attachment of a vacuum gauge or the like showing my new design;

FIG. 2 is a right side elevational thereof, the left side view being a mirror image thereto;

FIG. 3 is a top plan view thereof, the bottom plan view being a mirror image thereto;

FIG. 4 is a front elevational view thereof;

FIG. 5 is a cross-sectional view thereof as taken from line 5—5 of FIG. 4.

FIG.1**FIG.2****FIG.3****FIG.4****FIG.5**
